UNITED STATES PATENT OFFICE.

ADOLF SPIEL, OF BERLIN, GERMANY.

PETROLEUM-ENGINE.

SPECIFICATION forming part of Letters Patent No. 377,866, dated February 14, 1888.

Application filed June 30, 1887. Serial No. 242,946. (No model.)

To all whom it may concern:

Be it known that I, ADOLF SPIEL, of Berlin, Germany, have invented certain new and useful Improvements in Petroleum-Engines, of which 5 the following is a full, clear, and exact description.

The object of my invention is to provide certain new and useful improvements in the petroleum-engines for which I filed an application for Letters Patent on the 13th day of May, 1887, Serial No. 238,152.

The invention consists in the construction and arrangement of certain parts and details and combinations of the same, as will be fully 15 described hereinafter, and then pointed out in the claims.

Reference is to be had to the accompanying drawings, forming a part of this specification, in which similar letters of reference indicate 20 corresponding parts in all the figures.

Figure 1 is a side elevation of my improvement with parts in section. Fig. 2 is a plan view of the same with the cylinder in section. Fig. 3 is an enlarged sectional plan view of 25 the cylinder-head and its connections, and Fig. 4 is an end elevation of the same. Fig. 5 is a face view of the cam for operating the oil-pump and the igniting-valve, and Fig. 6 is an enlarged sectional end elevation of the oil-pump mechanism on the line $x-x$ of Fig. 1. Fig. 7 is a plan view of the same. Fig. 8 is 30 an enlarged sectional elevation of the igniting-pipe and connections.

On a suitably-constructed base, A, is mounted 35 the engine-frame B, which supports the cylinder D, in which operates the piston C, connected, by the pitman C' and the crank-arm C'', with the main shaft E, carrying the usual fly-wheel and pulley connected with the machinery 40 to be driven. On the main driving-shaft E is secured the gear-wheel E', which meshes into the gear-wheel E'', secured to the auxiliary shaft b, which is rotated once for every two revolutions of said main shaft E.

The auxiliary shaft b is provided with a cam, 45 m, adapted to operate the valve of the igniting-chamber and the oil-pump. On the cam m is formed an eccentric pin, f, passing through a vertical slot, c, formed in the pitman-head c', formed on the upper end of the pitman c'', 50 pivotally connected at its lower end with the pump-rod d of the pump d', fastened on the

base A and of any suitable construction. The length of the stroke of the pitman c'' can be regulated by a screw, r, screwing in the upper 55 end of the pitman-head c' and extending into the vertical slot c, so that the eccentric pin f strikes against said screw r in its upward motion, thereby lengthening or shortening the stroke of the pitman c'' according to the distance which said screw r projects into the vertical slot c.

The oil-pump d' is connected with the lower end of the oil-reservoir x, located inside of the base A. The aperture connecting said reservoir x with said pump d' can be increased or diminished by a valve, v'', held in a normal closed position by a spring, v', and connected with the spindle v, having its bearing in a tube, v', held on the outside of the base A. The 65 spindle v projects beyond the upper end of the tube v', and passes through the slotted projection u, carrying on top a collar, v'', held loosely on the spindle v, and adapted to engage a nut, v'', screwing on said spindle v. The projection u is placed above a pin, y, secured to the pitman c'', so that the latter, in its upward movement, engages said projection u, and thereby raises the spindle v, so that the valve v'' establishes connection between the oil-reservoir x and the pump d'. The oil can then 70 flow from the reservoir x into the pump d', and this amount of oil is forced out of the pump by a downward movement of the pump-rod d into the pipe a, extending upward and leading to a heating-pipe, p', opening into the igniting-pipe p, located at the rear end of the cylinder D.

The governor R is located on the base A and operates on the horizontal sliding shaft R', carrying a disk, u'', engaging the loop u', connected with the projection u, so that when the governor-balls fly out said shaft R' is moved inward, carrying along said loop u' and the projection u, so that the latter cannot be engaged by the pin y of the pitman c'', and the valve v'' remains closed until the speed of the engine diminishes and the governor again pushes the shaft R', the loop u', and the projection u outward, so that the pin y can engage 95 the projection u, as above described. The projection u' is raised a suitable distance, which is limited by the nut v'' before the valve-spindle v' and the valve v'' are raised.

It will be seen that the governor, which is connected with the spindle v , as above described, causes an upward movement of said spindle when the supply of oil from the reservoir x to the pump d' is shut off, so that the pump d' cannot force any oil through the pipe a into the heating-pipe p' , thus diminishing the speed of the engine and causing the governor to again place the valve v^2 in such a position as to admit oil regularly into the pump d' at the upward motion of the pitman c^2 , striking with its pin y against the projection u , as above described.

The auxiliary shaft b imparts a longitudinally-sliding movement by its cam m to the shaft b' , mounted in suitable bearings secured to the engine-frame B and the head F at the rear end of the cylinder D . Said cam m imparts a sliding motion to said shaft b' in the direction of the arrow a' , and the return movement of said shaft b' is accomplished by the spring s' , pressing with one end against a shoulder on said shaft b' and with its other end against one of the fixed bearings of said shaft b' . The shaft b' connects at its outer end with a lever, b^2 , supporting the valve b^3 , located in the cylinder-head F and adapted to permit the escape of the burned gases after the explosion in the cylinder D .

On the outer end of the shaft b' is also formed an incline, as plainly shown in Fig. 3, which operates against the valve n , located in the cylinder-head F . The valve n is adapted to be seated at its inner end, n' , on the aperture o , leading into the L-shaped channel o' , leading at one end o^2 into the interior of the cylinder D , and at its other end leading into the pipe h , provided with a valve, g , opening inward. Said pipe h supplies the necessary atmospheric air for forming part of the mixture for the explosion.

The valve n in its ordinary position is held against its seat by the spring n^4 ; but when the air in the cylinder D is compressed on the return-stroke of the piston C then the compressed air forces said valve outward until it rests against the stop n^5 . The inner end, n' , of the valve n has then opened communication between the channel o' and the igniting pipe or tube p , which is secured to the outer face of the cylinder-head F , and into which opens the pipe p' , above described. From the rear end of the igniting-pipe p leads the pipe a' into the channel o' , and said pipe a' is provided with a valve, a^2 , which opens inwardly to admit the vaporized oil into the cylinder, but closes on a backward pressure from the said cylinder.

The oil from the reservoir x , after being pumped through the pipe a , passes into the pipe p' , which opens into the middle of the igniting pipe or tube p , and which pipe p' is surrounded by a tube or chimney, p^2 , which has its interior heated by a lamp, as shown in Fig. 1, or it contains a body of highly inflammable character, which is held in such a state as to heat the pipe p' red hot, so as to ignite

the mixture in the cylinder whenever it is desirable that an explosion should take place. The oil passing through this heating-pipe p' is heated to a considerable degree, generally so as to vaporize, and finally passes into the pipe a' and into the channel o' after its temperature has been raised considerably.

The operation is as follows: The piston C in the cylinder D , when traveling forward, sucks in the air through the air-pipe h , and at the same time a quantity of oil is forced into the channel o' , through the pipes $a'a$, by the pump d' , and the two are mixed in said channel o' , and this mixture passes into the cylinder through the opening o^2 . On the return-stroke of the piston C the mixture in the cylinder is compressed; but when the piston is near the end of its stroke the cam on the shaft b releases the valve n , which is thus forced outward until it rests against the stop n^5 by the pressure of the compressed mixture in said cylinder. Part of this compressed mixture now passes into the igniting-tube p , and is ignited by the red-hot pipe p' , connected with said igniting-tube. The entire charge in the cylinder D is thus ignited, causing an explosion, the force of which propels the piston forward and imparts motion to the driving-shaft E . On the return-stroke of the piston C the valve n is again seated on the opening o , and the products of combustion are forced outward through the valve b^3 . The oil-pump d' draws oil from the reservoir x at the last return movement of the piston, and again forces the oil into the channel o' on the forward motion of the piston, as above described. Thus it will be seen that the piston makes two complete strokes to one movement of the oil-pump.

The construction of the oil-pump and the transmission of the oil from the pump to the cylinder are different from the construction shown in my previous application before referred to, and are not claimed in the same.

Having thus fully described my invention, I claim as new and desire to secure by Letters Patent—

1. In a petroleum-engine, the combination, with a cylinder and a piston traveling in said cylinder and imparting a rotary motion to the main driving-shaft, of an auxiliary shaft, b , connected with the main driving-shaft, and making one revolution to two strokes of said piston, the eccentric-pin f , formed on said auxiliary shaft b , the pitman c^2 , operated by said eccentric-pin f , and the oil-pump d , operated by said pitman c^2 , substantially as shown and described.

2. In a petroleum-engine, the combination, with a cylinder and a piston traveling in said cylinder and imparting a rotary motion to the main driving-shaft, of an auxiliary shaft, b , connected with the main driving-shaft, and making one revolution to two strokes of said piston, the eccentric-pin f , formed on said auxiliary shaft b , the pitman c^2 , having a vertical slot, c , into which said eccentric-pin f extends, the screw r , against which said eccentric-pin f operates, and the oil-pump d , oper-

ated by said pitman c^2 , substantially as shown and described.

3. In a petroleum-engine, the combination, with a cylinder and a piston traveling in said cylinder, of a main driving-shaft receiving a rotary motion from said piston, the auxiliary shaft b , receiving a rotary motion from said main driving-shaft and making one revolution to two revolutions of said driving-shaft, the cam m , secured on said auxiliary shaft b , the rod b' , receiving an outward motion from said cam m , the spring s' , imparting a return movement to said rod b' , said rod b' being adapted to open the outlet-valve b^3 and to close the igniting-pipe p by the valve n , substantially as shown and described.

4. In a petroleum-engine, the combination, with a cylinder and a piston traveling in said cylinder, of a main driving-shaft receiving a rotary motion from said piston, the auxiliary shaft b , receiving a rotary motion from said main driving-shaft and making one revolution to two revolutions of said driving-shaft, the cam m , secured on said auxiliary shaft b , the rod b' , receiving an outward motion from said cam m , the spring s' , imparting a return movement to said rod b' , the valve n , operated by said rod b' and closing the connection between the igniting-chamber and the cylinder, substantially as shown and described.

5. In a petroleum-engine, the combination, with a cylinder and a piston traveling in said cylinder, of a main driving-shaft receiving a rotary motion from said piston, the auxiliary shaft b , receiving a rotary motion from said main driving-shaft and making one revolution to two revolutions of said driving-shaft, the cam m , secured on said shaft b , the rod b' , receiving an outward motion from said cam m , the spring s' , imparting a return movement to said rod b' , the lever b^2 , operated by the extreme outer end of said rod b' , and the valve b^3 , supported by said lever b^2 and opening at the second return-stroke of said piston, so as to permit the escape of the burned gases, substantially as shown and described.

6. In a petroleum-engine, the combination, with the auxiliary shaft b , provided with the

cam m , carrying the eccentric-pin f , of the slotted pitman-head c' , the screw r , screwing in 50 said pitman-head c' , to increase or diminish the stroke of said pitman-head, the pitman c^2 , supporting said pitman-head, the oil-pump d' , operated by said pitman, the pin y , extending from said pitman c^2 , the spindle v , having a 55 projection, u , against which said pin y operates, and the spring-valve v' , connected with said spindle v and adapted to open and close alternately the opening leading from the oil-pump to its supplying-reservoir, substantially as 60 shown and described.

7. In a petroleum-engine, the oil-supply pipe a and the heating-pipe p' , into which said pipe a discharges, in combination with the igniting-pipe p , into which said pipe p' opens, 65 substantially as shown and described.

8. In a petroleum-engine, the oil-supply pipe a , the heating-pipe p' , into which said pipe a discharges, and the igniting-pipe p , into which said pipe p' opens, in combination with 70 the discharge-pipe a' , leading from said igniting-pipe p to the channel o' , the cylinder-head F , provided with said channel o' , and having an opening, o^2 , adapted to be connected with said igniting-pipe p , and the air-supply pipe 75 h , having a valve, g , and leading into said channel o' , substantially as shown and described.

9. In a petroleum-engine, the oil-supply pipe a , the heating-pipe p' , into which said pipe a discharges, and the igniting-pipe p , into 80 which said pipe p' opens, in combination with the discharge-pipe a' , leading from said igniting-pipe p into the channel o' , and also provided with a check-valve, a^2 , the cylinder-head F , provided with said channel o' , and having 85 the opening o^2 , adapted to be engaged with said igniting-pipe p , the air-supply pipe h , having a valve, g , and leading into said channel o' , and the valve n , for connecting said channel o' with the igniting-pipe p , and disconnecting it from the same, substantially as 90 shown and described.
